Primary Examiner — Jae Liang*Assistant Examiner* — Bryan C Gusman(74) Attorney, Agent, or Firm — Lewis Roca Rothgerber Christie LLP(57) CLAIM

The ornamental design for a table, as shown and described.

DESCRIPTION

FIG. 1 is a front perspective view of a first embodiment of a table showing my new design;

FIG. 2 is a top plan view thereof;

FIG. 3 is a side elevation view thereof, the four sides being identical due to the design's symmetry;

FIG. 4 is a front perspective view of a second embodiment of a table showing my new design;

FIG. 5 is a top plan view thereof;

FIG. 6 is a front elevation view thereof, the rear elevation view being a mirror image; and,

FIG. 7 is a right side elevation view thereof, the left side elevation view being a mirror image.

The second embodiment is shown with symbolic break lines and those portions of the article between the break lines form no part of the claimed design. The bottom of the table is not shown in the drawings or described in the specification. It is understood that the appearance of any part of the article not shown in the drawings or described in the specification forms no part of the claimed design.
